UNITED STATES PATENT OFFICE.

THOMAS E. PRAY, OF CHICAGO, ILLINOIS, ASSIGNOR TO GOODMAN MANUFACTURING COMPANY, OF CHICAGO, ILLINOIS, A CORPORATION OF ILLINOIS.

MINING-MACHINE.

1,384,404.

Specification of Letters Patent. Patented July 12, 1921.

Application filed August 9, 1920. Serial No. 402,349.

To all whom it may concern:

Be it known that I, THOMAS E. PRAY, a citizen of the United States, residing at Chicago, in the county of Cook and State 5 of Illinois, have invented a Mining-Machine, of which the following is a specification.

This invention relates to improvements in mining machines and more particularly to mining machines of the cutter chain type 10 provided with a cutter arm adapted to be moved horizontally along the face of the mine wall to cut a horizontal kerf thereunder.

The object of this invention is to provide 15 a simple and durable construction of a machine of the class above described.

The invention consists in the combination, construction, and arrangement of parts as will hereinafter be described in connection 20 with the accompanying drawings, and more particularly defined in the appended claim.

In the drawings, Figure 1 is a plan view of a mining machine of the longwall type constructed in accordance with my present 25 invention.

Fig. 2 is a view in side elevation of the mining machine shown in Fig. 1.

Fig. 3 is a view in partial cross-section taken on line 3—3 of Fig. 1, and drawn to 30 a larger scale than Figs. 1 and 2.

Fig. 4 is a transverse cross-section taken on line 4—4 of Fig. 1, and drawn on the same scale as Fig. 3.

Mining machines of the cutter arm type 35 are usually provided with a cutter chain (not shown) which is moved in a channel 10 about a cutter bar 11 and a suitable driving sprocket 12. In the present illustration, I have shown the cutter bar 11 as applied 40 to a mining machine of the well-known "longwall type", that is to say, a mining machine which is adapted to be moved by suitable draft devices with its longitudinal axis parallel to the face of the mine wall, 45 and with the cutter bar 11 projecting substantially at right angles from the machine. Machines of this class are usually arranged so that the position of the cutter bar 11 may be changed so as to cut on the opposite side 50 of the machine, as indicated in dotted lines in Fig. 1. The cutter bar swings about a vertical axis as it is moved from one side of the machine to the other, and is normally maintained in the plane parallel to the floor 55 of the mine upon which the machine rests.

Under operating conditions however, it sometimes is desirable to tilt the cutter bar out of its normal horizontal plane so as to follow rolling or uneven floor, and to maintain the cutter bar at the proper height. 60

In the present invention, I provide a simple construction for mounting the cutter bar on the machine frame A so as to afford rotation of the cutter bar from one side of the machine to the other, and also to afford 65 tilting of the cutter bar out of its normal horizontal plane at the will of the operator. This construction, in detail, includes the cutter bar 11, having a main body portion 13, forming the major portion of the cutter 70 arm, an offset portion 14 at the inner end of the cutter bar, and a pair of upright arms 15, 15. It will be observed that the body portion 13, offset portion 14 and the arms 15, 15 of the cutter arm are all cast in one piece, so as to form a strong and simple construction, easily machined and assembled. The arms 15, 15 of the cutter bar are pivotally mounted in suitable apertures on opposite sides of an annular ring 17 by means of 75 pivot rings 15^a, 15^a, each extending horizontally through one of said arms, and having its ends supported in the ring 17. Said ring is rotatably supported in a frame member 18, which may be integral with the main 80 frame casting 19 of the machine.

The ring 17 is retained in the main frame 18 by segmental retaining plates 17^b, 17^b, attached to the lower surface of the ring 17 by means of a plurality of bolts 17^b, 17^b. A 90 suitable upper plate 11^a and lower plate 11^b are attached to the body portion 13 of the cutter bar beyond the boundary of the machine frame 18, and form the upper and lower flanges, respectively, of the channel 10, 95 as shown. The cutter chain sprocket 12 is mounted on the lower end of a vertical spindle 16 extending vertically upward through the offset portion 14 of the cutter arm.

Means for driving the spindle 16 in all 100 permissible positions of the cutter arm comprises a horizontally disposed gear 20 driven by a pinion 27 having suitable driving connection with the motor. The gear 20 is mounted above the ring 17, and has a downwardly extending gear hub 21 which bears on a bearing ring 22 interposed between said gear hub 21 and the inner surface of the ring 17. The gear hub 21 is relatively 105 large in diameter, and has a hollow center- 110

portion 23 in which is located a universal joint 24 connecting the gear 20 to the upper end 16^a of the spindle 16. This universal joint is substantially in axial line with the 5 pivot pins 18, 18, and comprises a toggle member 24^a, a pair of oppositely disposed pins 25, 25 having threaded engagement with the gear hub 21, and a second pair of oppositely disposed pins 26, 26 at right angles to the first mentioned pins 25, 25, and attached to the upper end 16^a of the spindle 16. A cover plate 28 is superimposed above the gear 20 and is attached to the main frame 18 in any suitable manner, such as by 10 screws 29, 29.

Means for lubricating the various moving parts of the mechanism above described, comprises an oil reservoir 30 formed by a partition 31 preferably attached to the under surface of the cover plate 28, and provided with a plurality of orifices 32, 32, located above the hub 21 of the gear 20, and other orifices 33, 33 located above the toggle member 24^a of the universal joint 24.

25 The oil from the orifices 32, 32 is fed by gravity to an annular oil-retaining depression 34 about the upper face of the gear hub 21, and is distributed to the main bearing of said hub through oil holes 34^a, 34^a. 30 The outer edge of said depression 34 is preferably provided with a plate 35, having an overhanging edge so as to retain the oil that is thrown outwardly by centrifugal force while the machine is in operation. The 35 oil from the orifices 33, 33 is caught in a reservoir 24^b, formed in the toggle member 24^a, and reaches the pins 25, 25, and 26, 26 through oil holes 36, 36. A portion of the oil from the reservoir 24^b also passes 40 through a centrally disposed oil hole 37 into a passage 38 in the upper end of the spindle 16, and thence by gravity to the main bearing 39 of said spindle.

Means for tilting the cutter bar 11 comprises a bar 42, detachably connected at one end to a pin 43, carried by the cutter arm 11 adjacent the inner end of the body portion 13 of said arm; and at the other end to a rocking arm 44, extending transversely 45 across the rear end of the machine and pivoted at its center. The arm 44 may be con-

trolled by any suitable means, such as a screw 45, supported on the machine frame, and engaging a threaded sleeve 46, connected to one end of the arm 44. It will now be 55 seen, that by the manipulation of the screw 45, the bar 42 may be oscillated so as to tilt the cutter arm to any angle desired. When it is desired to shift the cutter arm 11 to the opposite side of the machine the bar 42 may 60 be detached and also moved to operating position on the other side of the machine, as shown in dotted lines in Fig. 1.

65 The preferred method of rotating the cutter bar and ring member 17, is by employing the draft mechanism of the machine (not shown) which may be attached temporarily to the pin 43 for the purpose of rotating the cutter bar 11, and ring 17 into the desired 70 position. The ring member 17 may be locked in any one of several positions by means of a pin 40 which engages in suitably disposed notches 41, 41 arranged about the outer periphery of said ring.

Having described my invention what I 75 claim as new and desire to cover by Letters Patent, is:

In a mining machine, the combination of a frame, a horizontally disposed ring rotatably mounted in said frame, a cutter bar 80 comprising a chain-supporting element having a raised offset portion at one end thereof provided with a pair of upwardly extending arms, each connected to said ring by a substantially horizontal pivot mounted on 85 opposite sides of the latter, upper and lower guiding flanges attached to said supporting element to form a channel about said cutter arm, a cutter chain adapted to move in said channel, a vertically disposed shaft extending through said offset portion of the cutter arm and having a driving sprocket for said cutter chain mounted on its lower end and in line with said channel, a horizontally disposed driving gear mounted on said ring, and a universal joint affording operative 90 connection between said shaft and said driving gear.

95 Signed in Chicago, in the county of Cook and State of Illinois, this 5 day of August 100 A. D. 1920.

THOMAS E. PRAY.
